CLAIM

I claim the ornamental design for a weeding tool, as shown and described.

DESCRIPTION

FIG. 1 is an exploded perspective view of a weeding tool, showing my new design;

FIG. 2 is a perspective view of a tool head of the design, a handle and file thereof omitted for clarity of illustration;

FIG. 2 is a perspective view of the file of the design, the handle and tool head omitted for clarity of illustration;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is a top plan view thereof; and,

FIG. 9 is a bottom plan view thereof.
